M. G. Huldris "Amoranto" Design for Plates of Cooking Stoves,
assigned to Ward Smith & Huldris, Troy, N.Y.
Patented April 14, 1857

Dec. 884

N. S. Neder, of Troy, N. Y.
Assignor to

Smith & Sheldon, of the same place.
Letters Patent No. 884. Dated April 14th 1857.

The schedule referred to in these Letters Patent and making part of the same

To all whom it may concern:

Be it known that I, N. S. Neder, of the City of Troy,
in the County of Rensselaer, and State of New York, have invented or produced
a new and original design, - called the "Amaranth" for Plates of Cooking

Dec. 884

Stoves: and I do hereby declare that the following is a full and exact description of the same; reference being had to the annexed photographic drawings making a part of this specification, in which Fig: 1 represents the lower front plate; Fig: 2, a foot; Fig: 3, a front fire-door; Fig: 4, the side fire door; and Fig: 5 the large door, and Fig: 6, the small one of the oven.

My ornamental design for the lower front plate, consists of the central bouquet A, surrounded by the ornamental moulding B; — both upon a plain ground. — For the foot, — of the combined flowers and buds C, upon the check-work ground D, bordered by the scroll leaves E. For the front fire-door, — of the central bouquet F, the top and the bottom double flowering scrolls G; and the check-work ground H. — For the side fire-door, — of the central bouquet I, the top and the bottom double flowering scrolls J, and the check-work ground K. For the large door of the oven, — of the central upright bouquet L, the right hand and the left double flowering scroll M, and the check-work backing N. For the small door of the oven, — of the central bouquet O, the top and the bottom double flowering scrolls P, and the check-work Q. —

What I claim as my invention or production and desire to secure by Letters Patent, is, the ornamental design for the lower front plate, foot and doors of a cooking stove, herein described and fully represented in the annexed drawings. —
